UNITED STATES PATENT OFFICE

130,561

DESIGN FOR A CONDIMENT HOLDER

Sewall Billings Vaughn, Boston, Mass.

Application September 5, 1941, Serial No. 103,179

Term of patent 3½ years

To all whom it may concern:

Be it known that I, Sewall Billings Vaughn, a citizen of the United States, residing at Boston, in the county of Suffolk and State of Massachusetts, have invented a new, original, and ornamental Design for a Condiment Holder, of which the following is a specification, reference being had to the accompanying drawing, forming a part thereof.

I claim:

The ornamental design for a condiment holder as shown.

SEWALL BILLINGS VAUGHN.
